UNITED STATES PATENT OFFICE.

WALTER H. KNIGHT, OF NEW YORK, N. Y.

ELECTRIC RAILWAY.

SPECIFICATION forming part of Letters Patent No. 455,340, dated July 7, 1891.

Application filed May 11, 1885. Serial No. 165,102. (No model.)

To all whom it may concern:

Be it known that I, WALTER H. KNIGHT, a citizen of the United States, residing at New York city, State of New York, have invented 5 certain new and useful Improvements in Electric Railways, of which the following is a specification.

My invention relates to contact devices for electric railways, adapted to maintain the electrical connection between a moving vehicle and an exposed line conductor substantially parallel with the railway. In practice it is impossible to always maintain an exact parallelism between the track of the railway and 10 the line conductor, and in consequence one extremity of a contact device must follow a path along the conductor, while the opposite extremity must follow an irregularly-divergent path traced by its point of connection 15 with the vehicle.

My invention consists in a contact device carried by the vehicle having its outer extremity pressed into contact with the line conductor and guided along it and its inner 20 extremity having a free laterally moving and swiveling connection to the vehicle, permitting all the necessary movements to accommodate the device to the irregular paths followed by its opposite ends, respectively.

I have shown the invention applied to a railway in which the line conductor is inclosed in a slotted conduit, the conduit serving to protect the conductor and its slot, both affording access to the conductor and guiding the 25 outer extremity of the contact device along the path followed by the conductor; and my invention further consists in constructions adapting the contact device to this specific form of railway.

In the accompanying drawings, Figure 1 is an end view of a car or locomotive, with road-bed and conduit in section. Fig. 1^a is a side elevation of the plow in position. Fig. 2 is a section of the plow on the line 2-2, Fig. 1^a, and 30 shows also a section of the conduit on a line at right angles to its longitudinal direction, and also a cross-section of the plow. Fig. 3 shows the point of attachment of the plow-support to the locomotive. Fig. 4 is a side view of the 35 plows when thrown out of the slot by an obstruction in the conduit or the derailment of the locomotive. Fig. 5 shows modified forms

of shoes or brushes for making contact. Fig. 6 shows the spring-hinge between the foot and cover, and Fig. 7 is a diagram of short-circuiting connections. 55

In the drawings, C represents the slotted conduit having the main conductors A A', which will usually be of opposite polarity, supported on insulating-pins from its sides. 60 These conductors have bare contact-faces, against which a contact—as a shoe or brush—connected with the locomotive constantly presses.

L represents the axle of an electric locomotive, and M one of the wheels on the track T. This locomotive is intended to be propelled by an electric motor connected to the wheels in a well-known manner, the motor being in constant electrical connection with the stationary conductors in the conduit by means of the plows and flexible conductors, as hereinafter described. The contact devices, one or both, are carried by the vehicle, whereby their weight is taken off of the supply-conductors and wear of the latter is avoided. To obtain a steady movement of the contact devices or plows, I suspend them from the truck-framing independently of the spring-support car-body in the following manner: 75

The axle L terminates, as usual, in a journal, which turns in box N, between which and the body of the car is the spring V. To the box N, I fasten a rod O, which extends first forward to the edge of the wheel, and then 80 transversely across the car to the box on the opposite end of the axle, which is a counterpart to the one shown at N. A second cross-bar O' is fastened to the tie-rod O², that extends between the forward and hinder boxes 85 on the same side of the car. To the middle points of these bars O O', respectively, are fixed the uprights Q Q', having slots at their upper ends and supporting between them the bar R, whose vertical height can be readily 90 adjusted by means of the slots and bolts by which it is connected to Q and Q'. Any other adjustable connection may be used or the adjustment introduced at any other point, its object being to raise or lower the contact parts 95 relatively to the fixed conductors A A'. The bar R is bent into the shape of a W to accommodate the axle L, which passes beneath it. From the two lower extremities of the W 100

are suspended, respectively, the two plows P P'.

Referring now to the improvements made by me in the construction of the contact device and its attachment to the car, which are described in detail hereinafter, I have provided in general a primary part consisting of an upright arm or shank, which is connected to the car by a loose or universal joint, comprising both vertical and horizontal axes, and permitting freedom of movement in all directions from the point of attachment of the contact device as a center; also, a secondary part which is hinged to the first-named part and has an independent up-and-down movement relatively thereto in a vertical plane, and, third, a spring which maintains a pressure-contact between the contact device and supply-conductor without interfering with the free movement of the contact device as a whole. This is accomplished by arranging the spring so that it bears upon the two parts of the contact device and partakes of the common movement which both parts have. Each of the plows consists of a shank extending through and wider longitudinally than the transverse width of the slot. Within and protected by this shank is a conducting-core E, which is preferably a flat strip of steel, and which carries at its upper end a binding-post K, and at its lower end carries a foot-piece e, connected to it by a hinge within the conduit, and a spring, (shown in detail in Fig. 6,) and having screwed to it the removable contact-shoe J. The tendency of the spring-hinge is to throw e up in a vertical plane into a position parallel, or nearly so, with E; but in operation it is bent down and the lower end caught under the lower edge of A or A'. It will be seen that the part e and shoe J have constantly a tendency to rotate about the axis of the hinge, which is parallel with longitudinal conductors A and A', but that this tendency is interrupted by J coming in contact with the conductor. This tendency will be maintained whatever the position of the axis, so that E can have a wide range of vertical play without affecting the contact of the shoe and the conductor. The various positions the shoe may assume are shown in the full and dotted lines of Fig. 2. The core E, being the carrier of the main current, is carefully insulated by the sheath b, which is preferably made of vulcanized fiber rendered waterproof by being soaked in oil, paraffine, or like material. On one side the sheathing b projects down behind the core, as at b', forming a protection against accidental contact of E or e with the opposite conductor. The core E is slipped into the sheath b and the whole then slipped into a guard G, of chilled cast-iron, which completely surrounds it, transverse pins p p, of insulating material, being driven through holes left in the material for that purpose.

Whenever guard G becomes worn by friction against the edge of the slot, it is easily

removed by driving out pins p p, when it may be turned end for end, so that the wear will come in a different place, or renewed entirely. These guards, being made as independent castings of chilled iron, are cheap, easily replaced, and will wear longer than any other substance.

The principle of a removable or wearing piece that protects the insulation and can be readily replaced independently of the insulated core and the supporting parts can be carried out in various ways, the one I have shown being the one at present deemed the best.

Around the guard G is placed a clamp F, held by screws at d d and provided with an upright f, which terminates in a hook that catches into an eye or hole in R. The joint S, formed by the hook and eye, is somewhat loose, so as to allow the plow to swing in any horizontal direction, as well as to have a swivel movement about a vertical axis, which in this case passes through the plow itself, and at the same time any vertical movement is prevented. This swivel movement, together with the lateral movement of the swiveling axis, allows the plow, which extends for some distance longitudinally in the narrow slot, to move easily around curves in the line. The lateral swing about a longitudinal axis permits considerable play of the car on the track without affecting the plow and the contact. It also permits the plow to be placed at some distance from the center of the car.

In my patent, No. 305,731, granted September 23, 1884, I have shown and claimed a plow with bearings allowing it a lateral movement, which in that case was a horizontal one, the plow sliding along the axle, which served as a guide and support. In the present case the lateral movement is about a center formed by the suspending-joint. The longitudinal swing of the plow about a transverse axis allows the plow to come out of the slot readily in case of accident, as will be hereinafter described. On each side of each plow is a lug m, on which is pivoted one end of the clevis g, which is of a sufficient width to embrace the plow. The two clevises of the two plows are linked together at l, forming a loose universal joint between them. The two plows thus connected are held tightly before and behind by flexible draw-chains H H', which are connected to some fixed part of the locomotive and which may be replaced by any flexible connection rod or bar. The chains are attached to the plow at a point just above the slot, which gives it a great mechanical advantage in drawing the plow. In this form of device it will thus be seen that the hook-and-eye joint is not relied upon to hold the contact device in a position to engage the conductor, but that this function is performed by the flexible mechanical drawing connections H H'. These connections partake of the lateral movement of the contact device, and by rea-

son of their attachment to the plow above the slot at a point below and to one side of the joint, which may be considered as a fulcrum for the plow, the natural tendency of the contact device to tip up on meeting an obstruction is resisted by the pull upon the chain, the hook-and-eye joint serving as means to hold the plow down against riding up bodily away from the conductor. This chain is made 10 comparatively weak, so that when any obstacle is encountered by the plow or by the shoe it will break, and the plows will be thrown out of the slot without injury in a manner that will be now described; but the contact device 15 will not become detached from the vehicle.

Just within the lips of the slot, which are formed by the steel rails *k k*, are the two wooden rails *I I*, bolted to *k k* and forming an insulating guard or lining. When it is necessary to insert a plow in the slot, the shoe and foot *e* are bent down until *e* and *E* are in line with each other, when it is slipped into the slot, the shoe being thinner than the width of the slot. The breadth of the shoe 20 is somewhat greater than the distance from wooden guard *I* to conductor *A'*, so that in entering the shoe first springs out against *I* and then slides off until it comes in contact with the face of *A'*, and finally comes around 25 under *A'* to its normal position. When the shoe is in its normal position, only a very severe accident—such as derailment or complete obstruction of the slot or conduit—can interrupt the contact between it and the conductor. 30

In the case of obstruction the draw-chain breaks, as above described, and then both plows turn on axes *S S'*, forming with their connecting-clevises a parallel-link movement, 35 as shown in Fig. 4. The shoes leave the conductors and strike the insulating-guards *I*, so that any arc that may be formed between either shoe and its conductor is not carried over to the iron of the conduit. When the 40 shoes are out of the slot, they are instantly folded up under the force of the spring-joint against the guards *G*, as is shown in Fig. 4. It is to be remembered that each shoe is in electrical connection with one terminal of the 45 motor, the circuit being completed during normal operation from one conductor, as *A'*, to the shoe, to core *E*, to binding-post *K*, and from thence through the motor to the other plow, and thence to the other conductor. 50 Both guards *G* are connected to the metal of the car, so that when shoes *J* come in contact with them the circuit is completed, as shown in diagram Fig. 7, between the terminals of the motor, which, being driven by the 55 momentum of the car, acts as a generator, and working through a circuit of low resistance a powerful brake is instantly given to the momentum of the car by consumption of its energy in working the generator. Whenever the 60 locomotive is derailed, the plows are pulled out of the slot without breakage of the chain. After the plows are out of the slot they ride 65

along on the corner of guard *G*, and no injury is done to the core or joint. It will be seen that this arrangement of plows will work 70 equally well in whichever direction the vehicle may be proceeding, as the plows can swing about their transverse axes in either direction with equal facility.

An equivalent to shoe *J* and foot *e* is shown 75 in Fig. 5, *J'* representing a brush instead of a shoe, and *J²* representing a shoe fixed directly onto a prolongation of *E*. Any other device adapted to give way under an obstruction may replace chains *H H'*. 80

It will appear by a consideration of the device described above, first, that the contact-piece is held positively in contact with the line conductor by a spring reacting on the rigid part of the contact device and ultimately upon the vehicle itself, and that this spring action is attained without interference with the flexibility of connection between the contact device and its support, which is essential to its complicated movements when 90 in action. This is accomplished in the example shown by having the upright shank or primary part capable of a free horizontal movement and provided with a secondary contact-piece having an independent spring 95 movement. The spring itself partakes of the movement of the primary part while giving the secondary part an upward pressure against the line conductor. I believe myself to be the first to devise a practicable contact 100 device for an electric railway which is carried on the vehicle, positively pressed by a spring into contact with the line conductor, and provided with all essential movements for accommodating itself to the inequalities 105 of its work.

Secondly, it will be apparent that the contact device, while supported in such a manner as to have all essential movements relatively to the vehicle, is attached thereto by a 110 flexible chain or similar device, which extends fore and aft to give it a firm drawing attachment without interference with the relative movements. This is also of my invention. 115

Thirdly, it will be evident that the free movement of the rigid contact device, which I have termed a "swiveling movement," about a vertical axis may be attained by any combination of freely-moving parts which will 120 give the requisite play. In the instance shown the vertical axis is substantially coincident with the axis of the plow; but this is not essential, and, while the hook-and-eye combines both the lateral movement with the 125 swivel movement, these two movements may obviously be at different points, this application being, broadly, for a contact device having these two movements. The plow has also a yielding contact with the line conductor, 130 which maintains the electrical connection whatever the jointed movements may be.

I claim—

1. The combination, in an electric railway,

- of a supply-conductor and an electrically-propelled vehicle with a contact device connected to the vehicle by a joint, permitting freedom of movement about a vertical axis, 5 and a spring maintaining the traveling engagement between the contact device and supply-conductor, but not interfering with the free movement of the contact device about the vertical axis.
10. 2. The combination, in an electric railway, of a supply-conductor and an electrically-propelled vehicle with an intermediate contact device connected to the vehicle by a joint permitting freedom of movement around a vertical axis, said contact device comprising a spring-actuated portion having an up-and-down movement to correspond to irregularities in the line of the conductor, whereby a pressure contact with the supply-conductor 15 is maintained without interfering with the free lateral movement about the vertical axis.
15. 3. The combination, in an electric railway, of a supply-conductor and an electrically-propelled vehicle with an intermediate contact device connected to the vehicle by a joint permitting freedom of movement around a vertical axis, said contact device comprising a hinged portion having an up-and-down movement into and out of engagement with 20 the supply-conductor, and a spring holding the hinged portion against the conductor, but not preventing the movement around the vertical axis.
25. 4. The combination, in an electric railway, of a supply-conductor and an electrically-propelled vehicle with an intermediate contact device connected to the vehicle by a joint permitting freedom of movement around a vertical axis, and a spring partaking of the 30 said movement about the vertical axis and maintaining the traveling engagement between the contact device and supply-conductor.
35. 5. The combination of the supply-conductor extending along an electric railway, an electrically-propelled vehicle, and an intermediate contact device consisting of a primary part having a free swiveling motion around a vertical axis and a spring-actuated contact 40 supported by said primary part and having an independent movement relative thereto.
45. 6. The combination of a supply-conductor, an electrically-propelled vehicle, and an intermediate contact device consisting of two parts, the first being jointed to the vehicle on a vertical axis and movable freely in either direction, the second being connected to the first, but having an independent movement in a vertical plane, and a spring tending to 50 move the said second part constantly in one direction, thereby maintaining electrical connection with the supply-conductor.
55. 7. The combination of the supply-conductor, an electrically-propelled vehicle, and an intermediate contact device consisting of two parts, the first being jointed to the vehicle on a vertical axis and movable freely in either 55 direction in a horizontal plane, and the second part being hinged to the first part and having an independent movement in a vertical plane with a spring bearing upon the two parts, respectively, whereby the spring does not interfere with the swiveling movement, but presses the contact device constantly into engagement with the supply-conductor. 70
80. 8. The combination of the supply-conductor, an electrically-propelled vehicle, and a contact device consisting of two parts hinged together, with a spring constantly holding the outer part in engagement with the supply-conductor, the contact device as a whole being jointed to the vehicle on a vertical axis and movable freely in either direction. 75
85. 9. The combination of a supply-conductor extending along an electric railway, an electrically-propelled vehicle, and an intermediate contact device supported independently of the supply-conductor, but maintaining a traveling connection therewith and having a free swiveling movement about a vertical axis. 90
90. 10. The combination of a supply-conductor, an electrically-propelled vehicle, and an intermediate contact device having at one end a contact pressed upward against the supply-conductor and at its other end a jointed connection to the vehicle, permitting movement of the contact device about a vertical axis. 95
100. 11. The combination, in an electric railway, of a supply-conductor, an electrically-propelled vehicle, and an intermediate contact device having its weight supported by the vehicle and consisting of a primary part having freedom of movement about a vertical axis and a contact-piece carried by said primary part and spring-pressed upward against the supply-conductor. 105
110. 12. The combination, in an electric railway, of a supply-conductor, an electrically-propelled vehicle, and an intermediate contact device consisting of two parts hinged together, with a spring pressing the outer part upward against the supply-conductor, the contact device as a whole having freedom of movement about a vertical axis. 110
115. 13. The combination, in an electric railway, of a supply-conductor, an electrically-propelled vehicle, and an intermediate contact device with jointed connections between the vehicle and contact device, permitting movement of the contact device upon vertical and longitudinal axes, respectively. 120
120. 14. The combination, in an electric railway, of a supply-conductor, an electrically-propelled vehicle, and an intermediate contact device consisting of a primary part having freedom of movement about a vertical axis and a contact-piece hinged to said primary part on a longitudinal axis, with a spring maintaining the traveling engagement between the contact device and supply-conductor. 125
125. 15. The combination, in an electric railway, of a supply-conductor extending along the line of way and an electrically-propelled vehicle 130

with an intermediate contact device connected to and having its weight supported by the said vehicle, whereby the said conductor is relieved of strain, and a joint having a vertical axis around which the contact device swivels freely.

16. The combination, with a longitudinal conduit and an inclosed supply-conductor, of a vehicle outside the conduit and a contact-plow extending into the conduit and connected with the vehicle through a swivel-joint, the axis of which passes through the plow.

17. The combination of a slotted conduit and inclosed supply-conductor with an electrically-propelled vehicle, a contact-plow consisting of a conducting-core and a protecting guard for the core, a support for the plow, and a swivel-connection between the plow and support, allowing movement on a vertical axis, whereby the plow may follow the sinuosities of the slot.

18. The combination, in an electric railway, of a supply-conductor, an electrically-propelled vehicle, and an intermediate contact device supported thereby, consisting of an arm or shank and a contact-conductor in circuit with the line conductor within and protected by said arm, with a joint permitting freedom of movement to the said contact device about a vertical axis.

19. The combination of a slotted conduit and inclosed supply-conductor with an electrically-propelled vehicle having its body supported on springs, and a contact-conductor extending into the conduit and supported from the truck independently of the car-body by a loose connection permitting a swiveling movement to the contact-conductor, whereby it may follow the sinuosities of the slot.

20. The combination, in an electric railway, of a slotted conduit, an inclosed supply-conductor, and an electrically-propelled vehicle with a contact-plow having its weight carried by the vehicle and consisting of a shank extending through the slot and protecting the contact-conductor, and a joint around which said shank moves on a vertical axis.

21. The combination, in an electric railway, of a slotted conduit, an inclosed supply-conductor, and an electrically-propelled vehicle with a contact-plow comprising a shank movable freely about a vertical axis, a contact-piece hinged to the said shank, and a spring pressing the contact-piece against the supply-conductor.

22. The combination, with a slotted conduit and inclosed supply-conductor and an electrically-propelled vehicle, of a contact-plow movable freely about a vertical axis and comprising a contact-piece having an independent movement in addition to the swiveling movement of the remainder of the plow.

23. The combination, with a slotted conduit and inclosed supply-conductor, of an electrically-propelled vehicle, a contact-plow guided by the slot and supported outside the conduit, a swivel-connection between the plow

and its support, whereby the plow may follow the sinuosities of the slot, and a contact-piece connected with the plow at a point within the conduit and having an independent movement relative thereto.

24. The combination of a slotted conduit containing the supply-conductors of an electric railway with a car, a frame depending from said car capable of lateral movement relative to the vehicle, and a contact device movable on a vertical axis extending from said frame into the conduit and taking current from the conductors.

25. The combination, with an electric locomotive, of a slotted conduit and two independent contact devices extending from said locomotive into said conduit in line with each other, and each having an independent swivel connection with the locomotive, whereby each may be independently movable about a vertical axis.

26. The combination, with a railway and an electric locomotive thereon, of a conduit, a supply-conductor therein parallel with the railway, and an intermediate contact device in yielding engagement with the supply-conductor and movable laterally about a horizontal axis.

27. The combination, with a railway and an electrically-propelled vehicle thereon, of a slotted conduit, a supply-conductor therein parallel with the railway, and a contact-plow having yielding engagement with the supply-conductor extending through the slot, and a jointed connection between said plow and the vehicle at a point outside the conduit, permitting movement of the plow about a longitudinal axis.

28. The combination, in an electric railway, of a conduit, an inclosed supply-conductor, and an electrically-propelled vehicle with a contact-plow guided by the slot and movable laterally about a longitudinal axis, and a contact-piece connected to the plow at a point within the conduit and having an independent movement to compensate for any minor irregularities in the line of the supply-conductor.

29. The combination, with a slotted conduit and an inclosed supply-conductor, of an electrically-propelled vehicle, a contact-plow extending down into the slot and movable laterally relatively to the vehicle, and a hinged contact-piece connected to the plow at a point inside the conduit and having an independent movement relatively to the remainder of the plow.

30. The combination, in an electric railway, of a conduit, a supply-conductor, and an electrically-propelled vehicle with an intermediate contact device consisting of an arm or shank, and a contact-conductor having yielding contact with the line conductor within and protected by said arm or shank, and a joint permitting lateral movement of the contact device about a longitudinal axis.

31. The combination, with a conduit and

inclosed conductor, of an electrically-propelled vehicle and an intermediate yielding contact device consisting of a conducting-core and a protecting-guard therefor and a jointed attachment between the said contact device and its support, permitting movement about a longitudinal axis.

32. The combination, in an electric railway, of a conduit, an inclosed supply-conductor, and an intermediate contact-plow consisting of an upright part extending down into the conduit and movable laterally relative to the vehicle and a contact-piece hinged to the upright part on a longitudinal axis at a point within the conduit.

33. The combination, in an electric railway, of a supply-conductor extending along the line of way with an electrically-propelled vehicle and an intermediate contact device jointed to the vehicle on a longitudinal axis and carrying a spring-actuated contact-piece for engagement with the supply-conductor.

34. The combination of an electric locomotive, a stationary supply-conductor, and a contact device for engagement therewith, having a hook-and-eye attachment to the vehicle.

35. The combination, with a railway-track, of a vehicle thereon, a conduit parallel therewith containing a supply-conductor and having a longitudinal slot, and a yielding contact-plow depending from said vehicle by a universal joint and extending into the slot.

36. The combination, with a conduit, an inclosed supply-conductor, and an electrically-propelled vehicle with a contact-conductor movable laterally relative to the vehicle, of a drawing connection connected to the contact-conductor and the vehicle at its two ends, respectively, whereby the contact-conductor is drawn along in operative position to engage the supply-conductor.

37. The combination, with a conduit, an inclosed supply-conductor, and an electrically-propelled vehicle, of an intermediate contact device for engagement with the inclosed conductor movable laterally relatively to the vehicle, and a drawing connection attached to the contact device at a point outside the conduit and extending forward to the vehicle, whereby the contact device is propelled along the conduit.

38. The combination, with a slotted conduit and inclosed supply-conductor, of a vehicle, a contact-conductor having its weight supported at a point outside the conduit and movable laterally thereto, and a drawing connection between the vehicle and the contact, permitting freedom of lateral movement.

39. The combination of a conduit, an inclosed conductor, an electrically-propelled vehicle, and an intermediate contact device movable laterally relative to the vehicle and adapted to be drawn along the conduit with a flexible mechanical drawing connection partaking of the lateral movement attached to the vehicle and contact device, respectively.

40. The combination, in an electric railway,

of a conduit, an inclosed supply-conductor, an electrically-propelled vehicle, and a contact device movable laterally relatively to the vehicle and supported so that the contact device is free to tip up on meeting an obstruction, with a drawing connection between the contact device and vehicle, attached to the former at such a point that the pull upon the drawing connection will oppose the tendency of the contact device to tip up, thereby insuring the maintenance of the contact device in its normal operative position.

41. The combination, in an electric railway, of a conduit, an inclosed supply-conductor, and a contact device movable laterally relatively to the vehicle and supported outside of the conduit, so that it is free to tip up on meeting an obstruction, with a propelling connection between the vehicle and contact device, attached to the latter at such a point that the strain upon the propelling connection will oppose the tendency of the contact device to tip up, thereby holding the contact device in engagement with the supply-conductor.

42. The combination, in an electric railway, of a conduit, an inclosed supply-conductor, and a contact device movable laterally relatively to the vehicle and adapted to be drawn along the conduit, with a drawing connection between the vehicle and contact device, attached to the latter in advance of its point of support, whereby the tendency of the contact device to tip up on meeting an obstruction is resisted.

43. The combination, in an electric railway, of a conduit, an inclosed supply-conductor, and an electrically-propelled vehicle with a contact device movable laterally relatively to the vehicle and supported outside of the conduit, and a propelling connection attached to the vehicle and to the contact device at a point below its point of support, whereby the tendency of the contact device to tip up on meeting an obstruction is opposed by the pull upon the drawing connection.

44. The combination of a conduit, an inclosed supply-conductor, and an electrically-propelled vehicle with a contact device movable laterally relatively to the vehicle, drawing connection between the contact device and vehicle, and means for holding the contact device down in a position to engage the supply-conductor.

45. The combination, in an electric railway, of a supply-conductor, an electrically-propelled vehicle and an intermediate contact device consisting of an upright rigid arm having a contact-piece at its outer end held by spring-pressure against the line conductor and seated at its inner end at a fixed point upon the vehicle by a loose connection, allowing universal freedom of movement to the contact device.

46. The combination, in an electric railway, of a bared line conductor and an electrically-propelled vehicle with an intermediate con-

tact device mounted upon the vehicle and having its weight carried thereby, and a loose connection between the vehicle and contact device at one end of the latter, permitting freedom of movement in all directions about said point of connection as a center.

47. The combination, in an electric railway, of a supply-conductor extending along the line of way, and an electrically-propelled vehicle whereby the weight of the contact device is taken off the supply-conductor, a loose connection between one end of said contact device and the vehicle, allowing movement of the said contact in all directions about said point of connection as a center, and a contact-piece forming an extension of the contact device at its outer end and maintaining a traveling connection with the supply-conductor.

48. The combination, with a supply-conductor, an electrically-propelled vehicle, and an intermediate contact device having a jointed attachment to the vehicle permitting lateral movement of the contact, but not holding the same in engagement with the supply-conductor, and a separate mechanical connection between the contact device and vehicle, holding the contact device in a position to engage the supply-conductor, whereby if the said connection breaks the contact device will break circuit with the supply-conductor, but will not become detached from the vehicle.

49. The combination, with the supply-conductor extending along the line of an electric railway, of an electrically-propelled vehicle, an intermediate contact device fulcrumed upon the vehicle, and a mechanical connection between the contact device at a point to one side of its fulcrum and the vehicle, holding the contact device in a position to engage the line conductor, the contact device as a whole having a lateral movement relatively to the vehicle.

50. The combination of two supply-conductors of opposite polarity extending along an electric railway, two independent contact devices engaging the two line conductors, respectively, and loose connections between the vehicle and contact devices permitting independent lateral movement to the said contact devices.

51. The combination, in an electric railway, of two supply-conductors of opposite polarity extending along the line of way with an electrically-propelled vehicle, two contact devices engaging the said supply-conductors, respectively, loose connections between the said contact devices and the vehicle, permitting freedom of lateral movement, and spring-actuated contact-pieces maintaining traveling electrical connection with the supply-conductors, the said contact devices being mounted on the vehicle, so that their weight is carried thereby.

52. The combination of two supply-conductors of opposite polarity, an electrically-propelled vehicle, and two contacts having

their weight carried by the vehicle and engaging the supply-conductors, respectively, with a jointed connection between the contacts and vehicle, permitting free lateral movement of the contacts, but not holding them in engagement with the conductors, and an independent flexible mechanical connection extending from the vehicle to the contacts at a point to one side of the joint, maintaining the contacts in operative position.

53. The combination, with a slotted conduit and two supply-conductors of opposite polarity therein, of an electrically-propelled vehicle, and two contact devices engaging the said supply-conductors, respectively, and connections between the vehicle and contact devices outside the conduit, permitting independent lateral movement of the said contact devices.

54. The combination, in an electric railway, with a slotted conduit and a supply-conductor therein, of an electrically-propelled vehicle, an intermediate contact device, and a horizontal axis at a point within the conduit around which the contact device moves.

55. The combination, in an electric railway, of a slotted conduit and a supply-conductor therein with an electrically-propelled vehicle, a contact-plow extending into the slot and movable laterally relatively to the vehicle, and a contact shoe or piece connected to the plow at a point inside the conduit and having an independent movement about a horizontal axis relatively to the remainder of the plow.

56. The combination of a supply-conductor extending along an electric railway with an electrically-propelled vehicle, an intermediate contact device supported independently of the supply-conductor and maintained in a position to engage the conductor by its connection to the vehicle, and a joint between the contact device and vehicle, permitting a free swiveling movement about a vertical axis.

57. The combination of a supply-conductor extending along an electric railway and an electrically-propelled vehicle with an intermediate contact device having a jointed connection with the vehicle, permitting a free swiveling movement about a vertical axis, and a mechanical connection between the contact device and vehicle acting to hold the contact device in a position to engage the supply-conductor.

58. The combination, with a longitudinal slotted conduit and an inclosed supply-conductor, of an electrically-propelled vehicle and a contact-plow wider longitudinally than the transverse width of the slot extending into the conduit and connected with the vehicle through a swivel-joint, the axis of which passes through the plow.

59. The combination, in an electric railway, of a longitudinal conduit and an inclosed supply-conductor with an electrically-propelled vehicle and a contact-plow wider longitudi-

nally than the transverse width of the slot of the conduit, comprising an upright shank held against fore-and-aft movement and a joint permitting movement of the plow around 5 a vertical axis.

60. The combination, with an electric railway and an electric locomotive thereon, of a conduit, a supply-conductor thereon, an electrically-propelled vehicle, and a contact device held against fore-and-aft movement by its connections with the vehicle and movable laterally about a horizontal axis.

61. The combination, in an electric railway, of a supply-conductor, an electrically-propelled vehicle having its body supported upon springs, an intermediate contact device supported from the truck independently of

the car-body and movable laterally relatively to the vehicle, and a flexible conductor forming the electrical connection with the motor. 20

62. The combination, with an electrically-propelled vehicle, of a line conductor, an intermediate yielding contact device supported on the vehicle by free connection, permitting lateral movement of the contact device relatively to the vehicle to enable it to follow the line conductor, and a chain or similar flexible device extending from a point near the outer end of the contact device to the vehicle. 25
